PUMP.

1,178,651.

Specification of Letters Patent. Patented Apr. 11, 1916.

Application filed September 20, 1909. Serial No. 512,678.

To all whom it may concern:

Be it known that I, MAURICE LEBLANC, a citizen of the Republic of France, residing at Villa Montmorency, Auteuil, Paris, France, have made a new and useful Invention in Pumps, of which the following is a specification.

This invention relates to air or other elastic fluid pumps and also to a method of pumping air or other elastic fluid.

In a co-pending application filed by me for United States Letters Patent, (matured on February 14, 1911, into Patent No. 984,278) I have described a fluid translating device comprising a partial injection type of rotatable impeller discharging into a collecting chamber or combining tube which, in turn, discharges into a diffuser. The device in said application is illustrated as applied to a condensing apparatus. In the device of said application, while the rotatable impeller discharges liquid therefrom in the form of films or leaves, the cross-sectional area of the combining or collecting chamber is such that the leaves upon, or immediately after, being formed and projected into the chamber are probably broken up into an infinite number of drops, like spray, because in said device the cross-sectional area of the combining or collecting chamber is such that the leaves or films of completely formed at the time they are discharged from the rotatable impeller, can only partially fill or bridge the chamber. In other words, the chamber is shown as substantially circular in cross-section and the liquid projected into one side of the chamber at most can only assume a fan-like form which can reach but a small portion of the entire wall surface of the chamber. As the air or steam or other elastic fluid can escape from between the successive leaves formed, it is probable that the leaves either at the time of formation or immediately thereafter are broken up, as before described. It has been found that such a device, while it makes an especially efficient condenser, does not make an air pump such as may be desired.

In still another co-pending application filed by me on September 14, 1909, Serial Number 517,691 for United States Letters Patent, I have disclosed an air or other elastic fluid pump in which such a partial injection type of rotatable impeller is utilized and in this device, by means of making the cross-sectional area of the combining or col-

lecting chamber such that the liquid leaves discharged by the rotatable impeller substantially fill or bridge it as a piston does a cylinder, I have been enabled to obtain a much more efficient air or other elastic fluid pump than the device of said first application makes. In the device, however, of said second pending application, I utilize substantially the same form of blades for the rotatable impeller as in the device of the first application and an object of this invention is to produce an air or other elastic fluid pump which will be superior to and more efficient than the device of said second application. In a general way, the device of said second application and the device of this application are the same, but in certain important details they differ.

The method of pumping air in accordance with this invention, which may be carried out by means of the device hereinafter described or by means of other devices than the one here described, broadly consists in confining air or other elastic fluid between adjacent leaves of a rapidly moving column or stream composed of a succession of liquid leaves, whereby the air or other elastic fluid is caused to move with the column and then in converting the velocity of the column into pressure.

In the drawings accompanying this application and throughout which similar elements are denoted by like characters: Figure 1 is a view in sectional elevation taken on the line 1-1 of Fig. 3 of an air or other elastic fluid pump embodying this invention; Fig. 2 is a sectional view taken on line 2-2 of Fig. 1, looking in the direction of the arrow; and, Fig. 3 is a top plan view of said pump.

The pump, broadly, consists of a rotatable impeller wheel provided with a row of axially-disposed blades. A distributor is located within the inner periphery of the row of blades and adapted to receive water or other liquid from some suitable source and to deliver it to a number of the blades less than the total number. The rotatable impeller, since the distributor distributes water or other liquid to a number of the blades of the impeller less than the total number, is therefore a partial injection impeller. The liquid thus distributed to the blades is projected by them at a high velocity and in the form of extremely thin sheets across a con-

duit or channel at a point between the inlet and the outlet of the channel. The channel or conduit has an inlet for elastic fluid to be pumped, a combining tube or collecting chamber for the propelling liquid and the fluid to be pumped and a diffuser wherein the stream formed of the liquid and fluid is compressed and from the outlet of which it is discharged. The conduit or channel at 5 the point of delivery of liquid from the blades is of such cross section and contour relative to the sheet or film of liquid discharged into it that the film completely, or substantially completely, blocks it off as a 10 piston does a cylinder. The bladed wheel or impeller is rotated by any suitable means, such as a turbine, electric motor or reciprocating engine, at such a speed that the peripheral speed of the blades will give to the 15 impelling liquid a high velocity and will project the leaves or films of liquid across the conduit and toward and through the diffuser. By making the conduit or channel as I have in the present case of such cross 20 section that the liquid leaves or films can completely, or substantially completely, fill the channel or span it as a piston does a cylinder, I find that I can approach the theoretical quantity of fluid which can be 25 moved for a given quantity of liquid at a given speed of liquid and I find that I can discharge the pump against a considerable, 30 head.

I find that the pump is especially applicable as an air pump for condensers of the surface, jet and barometric types and that by means of the same I am able to produce in such condensers the theoretical vacuum under wide ranges of conditions.

40 The pump preferably consists of a wheel or disk 5 mounted upon a shaft 6 and provided with an annular row of axially-disposed blades 7. The outer or free ends of the blades are provided with a shroud 8 while the inner ends are secured to the wheel by means of a foundation member 9. The inner walls of both the shroud and the foundation member are straight and parallel one to the other as shown at 10. The 45 shaft 6 is journaled in suitable bearings 11 and 12 and passes through stuffing boxes 13 and 14, the bearings and stuffing boxes being carried by the side plates or flanges 15 and 16 of the device. A central body member 17 is secured to the side plates or flanges 15 and 16 by means of two sets of bolts 18 and 19.

The side plate or flange 16 is formed with a chamber provided by the outer wall of the 50 side and an inner wall 20 joined to the side by means of a wall 21 which lies just within the row of blades 7. This chamber, which I will term the distributing chamber, is provided with an inlet 21' for water or other 55 impelling liquid and an outlet or distribut-

ing spout or nozzle 22 which simultaneously delivers water to a number of the blades of the wheel less than the total number. In the apparatus disclosed in the drawings it is formed so that it may deliver 70 to four or five blades at one time.

It will be seen that by loosening bolts 18, which pass through a retaining flange 23 and into the inner or body portion 17, the plate 16 carrying the distributing chamber 75 may be rotated about its axis and the distributing spout 22 adjusted to the proper position and by tightening these, the distributing spout may be locked in proper position.

Carried by the central or body portion 17 is the channel or conduit before referred to and composed of the inlet chamber 24, the collecting chamber or combining tube 25 and the diffuser 26. The collecting chamber or 80 combining tube 25 is formed in the nature of a bushing 27 secured within the main casting 17. As the liquid discharged from the rotatable impeller contacts with the walls of this chamber, it is preferably made 85 in the nature of a bushing so as to be renewable if necessary.

In order to prime the pump, an injector device is located adjacent to the inlet of the diffuser 26. This device consists of a 90 cone 28 seated between the main casting 17 and the diffuser and which forms the inlet end of the diffuser. Around this cone an annular chamber 29 is left and this chamber is provided with an inlet 30 for steam or 100 water under pressure as is desired, and by means of this device the pump may be primed.

In accordance with the provisions of the patent statutes, I have described the principle of operation of my invention, together with the apparatus which I now consider to represent the best embodiment thereof, but I desire to have it understood that the apparatus shown is only illustrative and 110 that the invention can be carried out by other means.

What I claim is:

1. In an air or other elastic fluid pump, a chamber provided with an inlet for fluid 115 and an outlet, a bladed impeller arranged so as to project liquid at a relatively high velocity in the form of films or leaves into said chamber between the inlet and outlet thereof and an adjustable distributor for 120 delivering liquid to a number of the blades of said impeller less than the total number.

2. In an air or other elastic fluid pump, a chamber provided with an inlet for fluid 125 and an outlet, an impeller provided with 130 blades and arranged so as to project liquid at a relatively high velocity in a sub-divided state into said chamber between the inlet and outlet thereof, an adjustable distributor for delivering liquid to said blades 135

- and means communicating with the outlet of said chamber for transforming fluid velocity into pressure.
3. In an air or other elastic fluid pump, a collecting and combining chamber, a diffuser communicating therewith, a rotatable impeller adapted to discharge liquid into said chamber and an adjustable nozzle for delivering liquid to said impeller.
- 10 4. In an air or other elastic fluid pump, a collecting and combining chamber, a diffuser in line therewith, a bladed rotatable impeller and adjustable means for distributing liquid to a number of blades of said impeller less than the total number.
5. In an air or other elastic fluid pump, a collecting and combining chamber, a diffuser, a rotatable impeller and adjustable means located within the periphery of said 20 impeller for distributing liquid to a number of blades thereof less than the total number.
6. In a fluid translating device, a chamber having a fluid inlet and a fluid outlet port, a combining tube and a diffuser communicating with the outlet port, and means for projecting liquid at a relatively high velocity into the combining tube, and through the diffuser, comprising an impeller, an annular row of laterally projecting blades mounted on and located concentrically with the impeller, a casing for the impeller comprising a central body portion surrounding said impeller, end plates 30 mounted on opposite sides of said central portion one of which is adjustable and is provided with a liquid distributing chamber and an inlet communicating with the chamber, and a distributer for delivering liquid from the chamber to the blades located within and communicating with the chamber, and mounted on said adjustable end plate.
7. In a fluid translating device, a chamber provided with an inlet for fluid and an outlet, an impeller having an annular row of laterally projecting blades mounted thereon for projecting liquid into said chamber and for discharging it through the outlet, a casing for the impeller having an adjustable end plate provided with a liquid distributing chamber and a liquid inlet communicating with the chamber and a liquid distributer for delivering liquid to the blades mounted on said adjustable end plate and communicating with said chamber.
8. In a fluid translating device, a chamber provided with an inlet for fluid and an outlet, an impeller, an annular row of blades mounted on the impeller, a casing for the impeller having a liquid distributing chamber formed therein and provided with a liquid inlet, an adjustable end plate forming a wall of the chamber and an adjustable distributer for delivering liquid from the chamber to said blades mounted on said end plate.
- In testimony whereof I have hereunto subscribed my name this third day of September, 1909.
